FINISH-REMOVER-APPLYING DEVICE.

1,139,358.

Specification of Letters Patent. Patented May 11, 1915.

Application filed July 31, 1911. Serial No. 641,605.

To all whom it may concern:

Be it known that I, CARLETON ELLIS, a citizen of the United States, now residing at Montclair, county of Essex, and State of New Jersey, have made certain new and useful Inventions Relating to Finish-Remover-Applying Devices, of which the following is a specification, taken in connection with the accompanying drawing, forming part of the same.

This invention relates especially to portable self-contained devices for applying finish remover, varnish or other liquid by pneumatic pressure generated in the portable tank by an inert or inflammability suppressing gas such as carbon-dioxid which may be supplied in the amounts required from a suitable interchangeable or replaceable container containing the liquefied or highly compressed gas.

In the accompanying drawings showing in a somewhat diagrammatic way illustrative embodiments of this invention, Figure 1 is a vertical section of a large form of the device. Fig. 2 is a similar vertical section through another form of the device; and Fig. 3 is a top view thereof, parts being broken away.

In the form of device somewhat diagrammatically shown in Fig. 1 and which is especially suitable for large sizes capable of containing forty or fifty gallons or more of remover or other liquid the tank 9, which may of course be stayed or reinforced, may be formed of any suitable material, such as sheet metal and preferably provided with an internal partition 20 forming a liquor compartment below and a gas container compartment 11 above this partition. The tank 10 may be provided with any suitable transporting devices, wheels or casters, such as 10, so as to facilitate its movement from place to place with a minimum of effort. The gas container compartment 11 is preferably provided with a container door 12 with a cover 32 which may be conveniently hinged to the tank by suitable hinges, such as 32, so that access may be more readily had to this upper or gas container compartment 11 when desired. The gas container may be in the form of a suitable interchangeable container or tank such are are commercially produced for many purposes and may be charged with liquefied or high pressure inert or inflammability suppressing gas, such as

carbon-dicoxid, nitrogen or the like. This container 1 may be connected in any desired way as by a suitable screw connection with the gas pressure pipe 4 and it is desirable to interpose in this connection a suitable pressure regulating valve 2 which may be of the automatic pressure regulating check valve type so as to maintain a substantially constant pressure beyond the valve. Also, if desired, a suitable pressure adjusting valve 33 may be used in connection with this gas pressure pipe so as to still further regulate the pressure of the gas delivered therethrough to the liquor compartment below. This pressure adjusting valve may have detachably connected therewith the adjusting handle 3 upon which may be mounted the indicator 18 cooperating with a suitable dial or scale 19 so as to be visible through the slot 24 in the cover.

The remover, varnish or other liquor 8 may be supplied from time to time to the liquor compartment through a suitable opening 30 therein which may be securely closed by a suitable cap 31 which may have a threaded or other suitable engagement therewith. It is also desirable for some purposes to have a supplemental pressure regulating or relief device connected with this liquor compartment, such as the safety valve 23 which may have its discharge opening cooperating with a suitable hole in the cover 39. This may of course be used to relieve the gas pressure in the liquor compartment before refilling the same with liquor. The pneumatic pressure of the inert gas upon the upper surface of the liquor renders non-inflammable and non-explosive the gaseous contents of this liquor compartment which is of course most important in connection with the filling operation and this carbon-dioxid or other inert gas also tends to reduce by absorption the flashpoint of the volatile inflammable liquids sometimes used in this connection and also to minimize inflammable action in the hose and other connections and applying devices which may have any suitable form. As indicated the delivery pipe 7 is carried down toward the bottom of the liquor compartment and may communicate with several applying devices through suitable valves 5, 6 which may govern the delivery of the remover or other liquid through the hose connections 13, 14 to suitable applying devices 15, 16 of any de-

sired description. The remover, for example, may thus be readily and quickly applied under the desired pressure to such parts as can be conveniently reached and then the portable self-contained tank may be moved along on the transporting devices connected therewith so as to cover other work. Of course, when the gas pressure in the container is undesirably low, the container may be readily disconnected and replaced by a fresh gas container inserted through the door 12 with slight expenditure of the workman's time and effort.

Another form of portable tank better adapted for smaller sizes is indicated in Figs. 2 and 3 in which the tank 17 may be given a cylindrical form and constructed of sheet metal in any desired way. The intermediate partition 20 separates the liquor compartment below from the gas container compartment 11 above the cover 37 of which may be movably secured in any desired way as by the hinges 32. The hinged door 12 may be provided substantially in line with the rear end of the gas container 1 so that the container may more conveniently be connected to the coupling devices and deliver the pneumatic pressure through the gas pressure pipe 4 so as to act upon the top of the liquor 8 in the compartment below. This gas pressure pipe may be provided with a suitable pressure regulating valve 2 and pressure adjusting valve 33 with which the adjusting handle 3 may be detachably connected so as to support the indicator 18 in coöperation with the scale 19 which may be conveniently read through the aperture 24 in top of the tank. The remover or other liquor may when desired be supplied to the filling aperture 25 which may be closed in any desired way and in the normal operation of the device this liquor is forced by the pneumatic pressure of the inert inflammability suppressing gas preferably though not necessarily used in this connection up through the delivery pipe 7 and connected hose or flexible connection 21 so as to be delivered in the desired amounts and at the proper pressure to the applying device 22 of any desired description. In this case also the supply of gas may be readily renewed at any time by disconnecting the empty container 1 and replacing it with a similar filled standard container containing liquefied carbon-dioxid, for instance, which has desirable inflammability suppressing action as previously explained.

Having described this invention in connection with a number of illustrative embodiments, forms, proportions, materials and arrangements of parts, to the details of which disclosure the invention is not of course to be limited, what is claimed is:

1. In finish remover applying devices, a portable tank provided with transferring

devices and provided with an internal partition forming a lower liquor compartment and an upper gas container compartment, a hinged cover and a container door communicating with said gas container compartment, a filling aperture and closing device therefor communicating with said liquor compartment, a delivery pipe and valved connections with applying devices communicating with said liquor compartment, a gas pressure pipe communicating with said liquor compartment, an automatic pressure regulating valve and a manual pressure adjusting valve connected with said gas pressure pipe and located in said gas container compartment, an adjusting handle to manually operate said pressure adjusting valve from outside said tank and an indicator coöperating with said adjusting valve, a safety and discharge valve communicating with said liquor compartment and an interchangeable gas container removably connected to said gas pressure pipe to supply carbon dioxid to said liquor compartment and pneumatically force the liquor therefrom while suppressing inflammability.

2. In finish remover applying devices, a portable tank provided with wheeled transferring devices and comprising a liquor compartment and a gas container compartment, means to supply liquor to said liquor compartment, valved delivery devices communicating with said liquor compartment, a gas pressure pipe communicating with said liquor compartment and a pressure regulating valve connected with said gas pressure pipe, a safety and discharge valve communicating with said liquor compartment and an interchangeable gas container removably connected to said gas pressure pipe to supply inert inflammability suppressing gas to said liquor compartment and pneumatically force the liquor therefrom while suppressing inflammability.

3. In finish remover applying devices, a portable tank provided with wheeled transferring devices and comprising a liquor compartment and a gas container compartment, means to supply liquor to said liquor compartment, valved delivery devices communicating with said liquor compartment, a gas pressure pipe communicating with said liquor compartment and an automatic pressure regulating valve connected with said gas pressure pipe and an interchangeable gas container removably connected to said gas pressure pipe to supply inert inflammability suppressing gas to said liquor compartment and pneumatically force the liquor therefrom while suppressing inflammability.

4. In finish remover applying devices, a portable tank provided with wheeled transferring devices and provided with an internal partition forming a lower liquor compartment and an upper gas container com-

partment, a hinged cover and a container door communicating with said gas container compartment, a filling aperture and closing device therefor communicating with said liquor compartment, a delivery pipe and valved connections with applying devices communicating with said liquor compartment, a gas pressure pipe communicating with said liquor compartment, an automatic pressure regulating valve and a manual pressure adjusting valve connected with said gas pressure pipe and located in said gas container compartment, an adjusting handle to manually operate said pressure adjusting

valve from outside said tank and in an indicator coöperating with said adjusting valve, a safety and discharge valve communicating with said liquor compartment and an interchangeable high pressure gas container removably connected to said gas pressure pipe to supply gas to said liquor compartment and pneumatically force the liquor therefrom.
